UNITED STATES PATENT OFFICE

CHARLES H. WINDSOR, OF PALMYRA, NEW JERSEY

SANITARY BASIN

Application filed November 6, 1929. Serial No. 405,193.

The present invention relates to sanitary basins, and has, as an object, the provision of an improved wash bowl structure adapted to receive and support a sanitary basin. The invention also relates to an improved combination of the wash bowl and a sanitary basin of novel construction, the latter being claimed, per se, in a copending application, Serial No. 441,078, filed April 2, 1930.

In working out the invention, it has been found desirable to provide a fixture upon which a sanitary basin may be readily positioned and removed after use, the fixture being adapted to suspend the paper basin by its margin in such a way that marginal portions of the paper basin intermediate the supports are spaced from the wall of the fixture bowl.

The invention relates to a bowl having the usual inlet spout or spouts, and a drain opening in its bottom. It seeks to provide a supporting means for the paper basin which is offset from the bowl wall in a direction outwardly from the latter. Substantially opposite supports are provided around the bowl wall in the area of the marginal slab portion of the fixture, the supports being preferably depressed below the top surface of the slab.

Moreover, an object of the invention is to provide supports which will receive marginal extensions of the sanitary basin and support the same so that the basin will not tilt or otherwise move during use. For this purpose, each support has opposite side walls extending upwardly from its supporting surface, and which are adapted to receive snugly therebetween marginal extensions of a paper basin.

In order that the invention may be clear to those skilled in the art, there are shown in the accompanying drawings several embodiments of my invention, but these are illustrative, and in no sense restrictive, of the invention, it being understood that variations from the illustrative and written disclosure may be made, and yet be within the range of my invention as defined in the 50 claims appended.

In the drawings:—

Figure 1 is a plan view of so much of a wash bowl and fixtures, of conventional design, as are necessary to illustrate the invention, with the individual basin in position. 55

Figure 2 is a view in vertical section of a wash bowl, with the individual basin in place, substantially on the line 2—2 of Figure 1.

Figure 3 is a fragmentary view in plan 60 illustrating a slightly modified form of the invention.

Figure 4 is a fragmentary view in plan, showing another slight modification.

Figure 5 is a detail sectional view of the 65 edge of the individual basin of the form embodying a fibrous basin portion with a stiffened metal rim.

Figure 6 is a view in plan showing a 70 slightly modified form of basin suspension.

Figure 7 is a sectional view on substantially line 7—7 of Figure 6.

Figure 8 is a vertical section showing the basin adapted to that type of wash bowl in which the water inlet is in the form of a 75 spout projecting from the inner wall of the bowl.

Figure 9 is a detail showing the basin in reversed position.

Referring to the drawings by numbers, like 80 numbers indicating like parts in the several views, 10 indicates a bowl of any preferred design and make-up, having the slab 11, and the usual fixtures 12, conventionally illustrated.

The individual basin is indicated at 13, and, as shown, will preferably follow generally the contour of the bowl 10, although of smaller diameter than the bowl, so as to leave an overflow area between the wall of the bowl 90 10 and the edge of the basin 13 at the front and rear of the basin between its ends.

The basin 13 will be formed of a thin light material, here shown of fibrous material, such as paper, and where the material used, such as 95 paper, can be readily folded, the blank forming the basin may be folded along the lines 14, so that, as produced, ready for use, it will be flat and capable of being distended to basin-like form by pressing it centrally to 100

cause the folds or creases 14 to open and distend the material into a rounded basin shape. Such a construction is described in detail in my Patent No. 1,538,016, granted May 19, 1925. In order to give the basin stability and make it self-supporting, its edge may be stiffened in various ways, one convenient form of providing the stiffened edge, where the basin is made of fibrous material, such as paper, being to secure to that edge a thin metal rim 15 formed of folded and properly crimped material such as metal, as shown in the detail views, Figures 5 and 6. Preferably, the lower ply of the metal rim 15 will be wider than the upper ply and have its edge bent slightly, as at 16, so as to form a rounded contact surface for the paper basin 13 when in distended position, thus eliminating any danger of cutting or tearing the paper against the edge of the lower ply of the rim 15.

The basin 13 will be provided at suitable points in its periphery with projections or offsets 17, two diametrically opposed offsets being here shown for purposes of illustration, although such offsets may be greater in number and differently disposed if desired. Where the form of the invention embodies a paper basin and the metal rim is adopted, these projections 17 will extend outwardly from the rim, and will preferably be formed integrally with the rim for the purposes of convenience in manufacture. These offsets should cover a considerable area, as shown, or in other words, be of considerable width so as to prevent forward or rearward tilting of the paper basin, which would be possible if the projections were narrow or pintle-like in design.

The purpose of the projections or offsets 17 is to support the basin, as shown in Figures 1 and 2, upon, or in the area of, the slab 11, and in the usual fixture the basin will be so disposed when in place that it will lie below the level of the outlets of the fixtures 12 and extend beneath them far enough to receive water therefrom. Where it is necessary to drop the individual basin deeper in the bowl in order to bring it below the level of the water outlets, which might be the case where the outlet is formed in the wall of the basin, the projections on the rim of the basin may be formed as shown in Figures 6 and 7, where the projections 18 are bent upwardly and then outwardly from the rim so as to give a supporting lip 19 to rest upon the slab and drop the basin deeper into the bowl so as to bring it below the level of the water outlets.

With an individual basin of this character, which is, of course, very light, but sufficiently strong to serve the needs of an individual user, it is desirable to prevent accidental shifting or movement of the basin on the slab while in use. This may be accomplished in various ways, as, for example, by provid-

ing opposite seats or supports 20, as shown in Figures 1 and 2, below the top of the slab at the proper points to receive the projections 17 or 19 on the basin, and these seats 20 may be readily formed in the slab or slab area. The seats should preferably be of such design and character as not to affect in any way the appearance of the slab or produce unsightly or unsanitary crevices. Their bottoms 20', which are offset outwardly from the bowl wall into vertical planes extending through the slab, may be inclined downwardly toward the bowl in order to cause water to drain therefrom.

Another way in which this result may be accomplished is by providing projections 21 on the surface of the slab, as shown in Figure 3, between which projections 17 or 19 on which the basin will rest. In both the form of Figure 3 and the form of Figures 1 and 2, it will be observed that the seats or supports for the rim extensions of the paper basin are disposed between substantially vertical walls in the slab area, these walls snugly receiving the rim extensions and preventing movement of the paper basin.

Still another way of accomplishing this result is to provide the projections 22 on the surface of the slab which will be engaged by apertures 23 formed in the projections on the basin, as shown in Figure 4.

It will be observed that the form of the invention shown in Figures 6 and 7 provide for dropping the basin by means of the dropped hanger supports down into the bowl, so that it would be adapted to take care of that type of fixture in which the water inlet is in the form of a spout projecting from the inner wall of the bowl, as distinguished from the old type of fixtures shown in Figures 1 and 2.

While this is a convenient and practical form of the device, there is shown in Figure 8 a construction which lends itself to use with that form of basin in which the projections on the basin are not offset, but are of the form shown in Figures 1 and 2. In this form of the invention, where there is provided a basin spout 24 below the top of the slab on the inner wall of the bowl, the seats 25 will be made deep enough to permit the supporting projections 26 to drop down to the inclined bottom 25' which is at a level, bringing the basin below the inlet spout 24, so that whichever form of wash bowl is provided, the straight-edge type basin may be used. In this form, as in the form of Figures 1, 2, and 3, the seats 25 are offset outwardly from the bowl wall into the slab area and have vertical side walls between which the rim extensions of the paper basin are closely received.

In all the various forms of fixture construction shown, including that of Figure 8, the supports or seats for the paper basin are offset in a direction outwardly from the bowl

wall into vertical planes extending through the slab. In all of these forms, the seats have side walls, the lugs 21 of Figure 3 constituting side walls. These walls serve to receive therebetween the marginal extensions of the paper basin and prevent shifting movement of the paper basin in use. In the several forms, with the exception of Figure 3, the seats are depressed below the top surface of the slab, whereby the continuity of the smooth upper surface of the slab is not interfered with, as in the form of Figure 3, wherein the side walls or lugs 21 constitute upward projections.

As shown in Figure 9, that form of the invention in which the supporting projections 27 are offset may be used, if desired, by simply reversing it, as shown, so that the offset projections 27 form supporting feet, and the basin reversed in this way can be used as an ordinary standing basin, as distinguished from its use in connection with a wash bowl. It is obvious that the perpendicular members 28 of the offset supports 27 may be made of sufficient length to maintain a relatively shallow bowl 29 in reversed position for use as a hand basin, without interfering with its use in connection with a wash bowl. Although the contour of the projections shown in Figures 8 and 9 is not illustrated, it will be understood that they are of the same relatively wide design as the projections 17 of Figures 1 and 3, so as to avoid tilting of the basin.

It will be seen that by forming the basin projections integral with the folded rim and compressing the folded metal, a very rigid and stable offset is provided which will not sag or give under ordinary use. Moreover, it will be observed that in all of the several forms, the supporting projections on the tapered base are disposed entirely at the ends which permits unobstructed spaces for overflow from the tapered base intermediate its ends, when the basin is arranged in the bowl, as illustrated in Figure 1. Although the projections are described as being of considerable width, it will be understood that the underlying idea is to arrange them so that they support the basin throughout a considerable area at its ends, as distinguished from a relatively narrow or trunnion-like support, which would permit the basin to tilt as the water contained therein is agitated. Therefore, it is simply necessary that the projections or supports be of sufficient extent to prevent tilting of the basin.

The advantages of the invention disclosed are that an individual wash basin is provided which may be dispensed at small cost to the public and provide each user with a sanitary device, which, after once being used, may be thrown away, although it will be understood that the make-up of the individual basin is such that it is capable, in the hands of the individual user, of a very considerable use

without deterioration. It is intended, however, that where such basins are dispensed, either by attendants in toilet rooms, or through vending machines, by which the basin may be very readily handled, there shall be no common use of the basin by the public, and thus the danger of contamination by promiscuous use of wash bowls in public places is eliminated. The construction lends itself to rapid and cheap production, so that the basin may be turned out in large numbers and sold to the public at reasonable cost.

The advantages of the various form of fixture construction have been set forth, and it will be appreciated that the usual type of fixture has been adapted to a sanitary basin of my improved construction with only slight modification.

As stated, the disclosure here is illustrative, and such variations from the particular disclosure as are within the skill of the mechanic may be made without departing from the range of my invention.

I claim:

1. A basin having a bowl provided with a drain opening in its bottom, a water inlet spout, said bowl having surrounding the same at its top a marginal slab portion and below the surface of said slab portion substantially opposite supports of less extent than the bowl circumference, but of substantial width to engage marginal extensions of a collapsible basin positioned in said bowl throughout the greater portion of the basin width and prevent tilting thereof, said supports being offset outwardly from the bowl wall into vertical planes extending through the slab portion and disposed below the horizontal plane of the water inlet, whereby to suspend a collapsible basin having marginal extensions adapted to rest upon said supports with a portion of the basin beneath said inlet, the basin above said supports being substantially open and unobstructed by said slab portion whereby a collapsible basin may be readily deposited on and removed from said supports.

2. A basin having a bowl provided with a drain opening in its bottom, a water inlet spout, said bowl having surrounding the same at its top a marginal slab portion and below the surface of said slab portion substantially opposite supports each support having substantially vertical side walls extending upwardly therefrom to the surface of the slab portion and being of less extent than the bowl circumference, but of substantial width to engage marginal extensions of a collapsible basin positioned in said bowl throughout the greater portion of the basin width and prevent tilting thereof, each of said supports opening into the bowl and being offset outwardly from the bowl wall into vertical planes extending through the slab portion and disposed below the horizontal

- plane of the water inlet spout, whereby to suspend a collapsible basin having marginal extensions adapted to rest upon said supports with a portion of the basin beneath said spout, the basin above said supports being substantially open and unobstructed by said slab portion whereby a collapsible basin may be readily deposited on and removed from said supports.
3. A basin having a bowl provided with a drain opening in its bottom, a water inlet spout, said bowl having surrounding the same at its top a marginal slab portion and below the surface of said slab portion substantially opposite supports each of less extent than the bowl circumference, but of substantial width to engage marginal extensions of a collapsible basin positioned in said bowl throughout the greater portion of the base and width and prevent tilting thereof, said supports being offset outwardly from the bowl wall into vertical planes extending through the slab portion and disposed below the horizontal plane of the water inlet spout, whereby to suspend a collapsible basin having marginal extensions adapted to rest upon said supports with a portion of the basin beneath said spout, the basin above said supports being substantially open and unobstructed by said slab portion whereby a collapsible basin may be readily deposited on and removed from said supports, said supports each opening into and being downwardly inclined toward the bowl.
4. In combination, a basin having a bowl provided with a drain opening in its bottom, a water inlet spout, said bowl having surrounding the same at its top a marginal slab portion, said slab portion having at each end of the bowl a pair of spaced vertically disposed walls and therebetween a support adapted to receive a marginal extension of a collapsible basin, said walls being spaced a sufficient distance to receive an extension of substantial width, whereby the basin may be supported therebetween throughout the greater portion of the basin width, and an extension supporting surface between said walls disposed below the plane of the water inlet spout, whereby to suspend a collapsible basin with a portion thereof below said inlet, the basin above said supports being substantially open and unobstructed whereby a collapsible basin may be readily deposited on and removed from the supports, and an imperforate collapsible basin adapted to be disposed in said bowl with a portion beneath said spout, the collapsible basin being formed with marginal extensions adapted to fit on said supports between said walls to suspend the collapsible basin with its edge intermediate the supports spaced from the bowl wall.
5. In combination, a basin having a bowl provided with a drain opening in its bottom, a water inlet spout, said bowl having sur-

rounding the same at its top a marginal slab portion and below the surface of said slab portion substantially opposite supports of less extent than the bowl circumference, but of substantial width to engage marginal extensions of a collapsible basin positioned in said bowl throughout the greater portion of the basin width and prevent tilting thereof, said supports being offset outwardly from the bowl wall into vertical planes extending through the slab portion and disposed below the horizontal plane of the inlet spout, whereby to suspend a collapsible basin having marginal extensions adapted to rest upon said supports with a portion of the basin beneath said spout, the basin above said supports being substantially open and unobstructed by said slab portion whereby a collapsible basin may be readily deposited on and removed from said supports, and an imperforate collapsible basin adapted to be disposed in said bowl with its margin intermediate said supports spaced from the bowl wall, the margin thereof at said supports having extensions overlying said supports and suspending the basin while resisting tilting movement.

In testimony whereof I have hereunto set my hand.

CHARLES H. WINDSOR.
